CLAIM

We claim the ornamental design for a funnel for household use, as shown and described.

DESCRIPTION

FIG. 1 is a perspective view of a funnel.

FIG. 2 is perspective view of the funnel in FIG. 1 with some external surfaces in hidden lines. The hidden lines in FIG. 2 are claimed and are shown as hidden lines to show the shape and location of an internal component that is visible in FIGS. 7 and 8.

FIG. 3 is a side view of the funnel.

FIG. 4 is another side view of the funnel.

FIG. 5 is an end view of the funnel.

FIG. 6 is another end view of the funnel.

FIG. 7 is a top view of the funnel; and,
FIG. 8 is a bottom view of the funnel.
